UNITED STATES PATENT OFFICE.

JOHN W. FORD, OF FINDLAY, OHIO.

SPIKE.

No. 835,944.

Specification of Letters Patent.

Patented Nov. 13, 1906.

Application filed August 9, 1905. Serial No. 273,462.

To all whom it may concern:

Be it known that I, JOHN W. FORD, a citizen of the United States, residing at Findlay, in the county of Hancock, State of Ohio, have 5 invented certain new and useful Improvements in Spikes; and I do hereby declare the following to be a full, clear, and exact description of the invention, such as will enable others skilled in the art to which it apper-
10 cians to make and use the same.

This invention relates to railroad-spikes.

One object of the invention is to provide an exceedingly simple, inexpensive, durable, and efficient spike.

15 Another object of the invention resides in the provision of a spike embodying such characteristics that accidental withdrawal thereof from the base in which it is driven will be prevented.

20 With these and other objects in view the present invention consists in the combination and arrangement of parts, as will be hereinafter more fully described, shown in the accompanying drawings, and particularly 25 pointed out in the appended claims, it being understood that changes in the form, proportion, size, and minor details may be made within the scope of the claims without departing from the spirit or sacrificing any of 30 the advantages of the invention.

In the drawings, Figure 1 is an elevation of my invention, partly in section, illustrating the spike driven into a tie. Fig. 2 is a perspective view of the lower portion of the spike 35 without the key. Fig. 3 is a perspective view of a portion of the key.

Referring now more particularly to the accompanying drawings, it will be seen that the present spike comprises a body 1, having 40 one face at its lower end directed outwardly over the body, as at 2, and then converging downwardly and meeting the convergent opposite face 3, as at 4, to provide the sharp cutting edge of the spike. Formed 45 upon the inclined portion 2 of the said enlargement intermediate the sides of the body 1 of the spike is a lip 5, which is arranged in direct alinement with an inclined rectangular or other-shaped opening 6, formed through 50 the spike from front to rear. The upper face of the said lip 5 is inclined corresponding to the inclination of the bottom of the opening 6.

The reference character 7 designates a key 55 whose lower portion is slotted, as indicated by the reference character 8, to form the fin-

gers 9, 10, and 11. This key 7 is made of comparatively thin material, and the fingers 9, 10, and 11 are therefore bendable.

In the use of my improved spike the body portion 1 is driven into the tie or other material and by reason of the enlarged portion at the lower end thereof the key 7 may be also readily driven into the tie or other material adjacent the rear face of the body 1. By 60 reason of the inclination of the top of the lip 5 and the opening 6 the driving of the key 7 will cause the intermediate finger 10 to pass through the said opening 6 and the end fingers 9 and 11 to bend outwardly in a plane 70 corresponding to the inclination of the inclined portion 2 of the aforesaid enlargement. It will thus be seen that the intermediate finger 10 is directed in a plane opposite to the plane in which the fingers 9 and 11 are 75 directed, and obviously by reason of the position assumed by these fingers 9, 10, and 11 with respect to the body 1 of the spike accidental withdrawal of the spike is positively prevented. It will be observed that 80 the fingers 9 and 11 have their extremities beveled, as at 12 and 13, respectively, opposite to the plane of bevel 14 of the intermediate finger 10. The beveling of the fingers in this manner in accordance with 85 the inclined surface of the body 1, with which they contact, facilitates the positioning of the fingers of the key 7 with respect to the body 1 of the spike.

What is claimed is—

1. A spike comprising a body portion having an opening through its lower end portion and a key having bendable fingers at one end, one of which is adapted to pass through said opening of the body portion, and means for 95 directing the remaining fingers in a different direction and away from the body portion.

2. A spike having a transverse opening therethrough and a key comprising a plurality of terminal fingers, said key being adapted to lie against a face of the spike through which the opening is formed, and said spike having means for directing a finger into the opening and having means for directing the remaining fingers in a direction away from 105 the spike.

In testimony whereof I affix my signature in presence of two witnesses.

JOHN W. FORD.
